BLOUSE OR THE LIKE

Phillis Knight, Bound Brook, N. J.

Application May 21, 1954, Serial No. 30,603

Term of patent 3½ years

(Cl. D3—25)

Fig. 1 is a front elevation of a blouse, embodying my new design.

Fig. 2 is a back elevation of the blouse.

I claim:

The ornamental design for a blouse or the like, as shown.
